UNITED STATES PATENT OFFICE.

JAMES J. GOUGH, OF CHICAGO, ILLINOIS, ASSIGNOR TO CHICAGO ELECTRIC MANUFACTURING CO., OF CHICAGO, ILLINOIS, A CORPORATION OF ILLINOIS.

PARKING LAMP.

Application filed July 22, 1925. Serial No. 45,208.

To all whom it may concern:

Be it known that I, JAMES J. GOUGH, a citizen of the United States, and residing at Chicago, in the county of Cook and State of Illinois, have invented a new and Improved Parking Lamp, of which the following is a specification.

My invention relates to lamp constructions and in some of its general aspects provides simple means for supporting an ordinary lamp bulb within a lamp casing, for making the electrical connections to the same, and for switching the lamp bulb on and off.

More particularly, my invention provides novel means for mounting a lamp bulb holder on the base of a lamp casing and provides a novel switch arrangement for controlling the circuit to the lamp bulb. Further and more detailed objects will appear from the following specification and from the accompanying drawings, in which—

Fig. 1 is a side elevation of a parking lamp embodying my invention.

Fig. 2 is an enlarged vertical and longitudinal section through the same lamp.

Fig. 3 is a horizontal section taken through Fig. 2 along the line 3—3, with the lamp bulb detached.

Fig. 4 is a section taken through the base portion of the lamp along the line 4—4 of Fig. 3.

Fig. 5 is a bottom view of the base portion of the lamp.

Fig. 6 is a plan view of the upper insulator employed in the base of the lamp.

Fig. 7 is an enlarged horizontal section taken along the line 7—7 of Fig. 1, showing the switching element in two positions.

Fig. 8 is a perspective view of the main portion of the slidably mounted switching member and Fig. 9 is a perspective view of the companion or knob-carrying portion of this switching member.

Fig. 10 is a plan view of the lower insulator employed in the base of the lamp drawn on a reduced scale.

In its immediate commercial applications, my invention is particularly suited for use in the construction of parking lamps adapted to be attached to the fenders of automobiles so as to afford the needed indication of the presence of a parked vehicle, while employing a lamp bulb of smaller current consumption than that of the usual headlight or

tail light. I am therefore illustrating and describing the various features of my invention in such an embodiment, although I do not wish to be limited to their employment in this particular connection.

The illustrated embodiment shows a parking lamp having a base 1 carrying a pair of downwardly projecting bolts 2 for fastening the base to the fender of an automobile. Telescoped over a cylindrical riser flange 3 on this base and secured to it by a screw 4 is the tubular portion 5 of a casing having two oppositely directed openings closed respectively by lenses 6 and 7.

Secured to the base 1 by a pair of rivets 8 are a pair of substantially flat insulators 9 and 10, shown separately in Figs. 6 and 10, which insulators clamp the shank 11 of a substantially U-shaped lamp-bulb holder between them. This holder is made of resilient metal with the shanks 12 thereof extending vertically and concaved towards each other at their upper ends so as to clamp the usual metal collar 13 on the base of a lamp bulb 14 between them, and each shank 12 has a lateral wing-shaped to afford a notch 14 for interlocking with one of the usual lateral pins on the base of the lamp bulb. One of the shanks also has an oppositely directed auxiliary wing 15 disposed for engaging the switching element 26 as hereafter described.

Secured to the upper insulator 10 is a binding post 16 to which a circuit terminal wire 17 may be fastened as shown in Fig. 3, the other terminal of the circuit being grounded to the metal casing through the metal frame of the automobile in the usual manner. The fastening of the binding post 16 to the insulator 10 also serves for clamping a resilient contact member 17 to the upper insulator, and this contact member extends between the shanks of the U-shaped lamp-bulb holder so as to engage the axial base terminal 18 of the lamp bulb as shown in Fig. 2.

The tubular casing portion 5 is provided with a slot 19 extending circumferentially thereof for guiding the switching member of the device. This switching member consists of a switching element 26 and of an actuating element which serves both for securing the switching element 26 to the casing and for presenting an exposed knob 20 by means of which the switching element 26

may be slid back and forth circumferentially of the casing. To connect the two parts of the switching member, I provide the switching element 26 with a pair of slots 21 and 5 provide the companion element with a pair of arms 22, which arms are of a width corresponding to the width of the slot 19. Each of these arms extends through one of the slots 21 and has its free end bent over the 10 inner face of the switching element 26 as shown in Fig. 7, so as to secure the latter element to the casing. One end of the switching element 26 is bent inwardly so as to afford a finger 23 adapted to engage the 15 auxiliary wing 15 on one of the shanks 12 of the metal lamp-bulb holder, and this finger desirably is indented as shown in Fig. 7 so that it will yieldingly interlock with the end of the wing 15 when the switching member is moved from the circuit-opening position (shown in full lines in Fig. 7) to its circuit-closing position as shown in dotted lines in the same figure. Furthermore, the main portion of the switching element 26 is initially formed of a general curvature greater in radius than the bore of 20 the tubular casing portion 5, so that the fastening of this switching element to the casing by means of the digitally movable fas- 25 tening element will flex the element 26 to a reduced curvature, thereby forcing it into a frictional engagement with the bore of the casing so as to prevent accidental displacement of the switching member from 30 any position to which it has been manually moved. By making the spaced arms 22 of a width corresponding to that of the slot 19, I enable these to guide the switching element 26 so as to restrict the latter to movements 35 circumferentially of the tubular casing portion, and by providing the fastening element of this switching member with an enlarged head 20, I avoid the necessity of employing auxiliary fastening elements. 40 45 To avoid a grounding of the metal holder through a possible tilting of the bolts 2, I desirably provide the lower insulator 9 with a pair of upwardly projecting wings 24, each of which extends between one arm 12 of the 50 lamp-bulb holder and the head of one of the bolts 2.

Thus constructed, and with the bore of the tubular casing portion of a diameter greater than the bulb of the lamp-bulb, a 55 removal of the screw 4 permits the main portion of the casing to be lifted off the base, thereby affording convenient access to the binding post 16 and permitting a removal or replacing the lamp bulb. By 60 clamping the bight of the holder between the central portions of the two insulators, I provide a convenient fastening for this holder without electrically connecting it to the casing, thereby securing a quite simple 65 construction suitable for use with a circuit

which has one side grounded in the usual manner.

However, while I have illustrated and described my invention in a highly desirable embodiment, I do not wish to be limited to the details of the construction and arrangement here disclosed, it being obvious that many changes might be made without departing either from the spirit of my invention or from the appended claims. 75

I claim as my invention:

1. In a lighting device of the class described, a metallic casing including a base, a substantially U-shaped bulb holder having its bight secured to the base, a lamp bulb having its base gripped between the arms of the holder, means insulating the holder from the casing, a resilient contact member disposed for engaging the axial terminal of the lamp bulb, and a switching member movably mounted on the casing for movement circumferentially of the latter, the switching member being disposed for engaging the tip of one arm of the holder. 80

2. A lighting device as per claim 1, in which the switching member has its arm-engaging portion formed for interlocking with the said tip to hold the switching member yieldingly in its circuit-closing position. 90

3. In a lighting device, a lamp bulb, a U-shaped holder gripping the base of the lamp bulb between its arms, a supporting base, a pair of overlapping insulators disposed on the base and extending respectively under and over the bight of the U-shaped holder, means spaced from the holder for fastening the overlapping insulators to the base so as to secure the holder rigidly to the base, a contact member extending into the holder and engaging the lower end of the lamp bulb, a switching member movable into and out of contacting relation to the holder, and two threaded members respectively at opposite sides of the holder and extending through the base for securing the device to a support, one of the insulators having portions thereof extending longitudinally of the holder between the latter and the threaded members. 100

4. In a lighting device of the class described, a metallic casing having a base, a substantially U-shaped bulb holder having its bight secured to the base, a lamp bulb having its base gripped between the arms of the holder, means insulating the holder from the casing, a resilient contact member disposed for engaging the axial terminal of the lamp bulb, and a switching member mounted on the casing and adapted to be moved into and out of contact with the holder, the casing having a slot extending circumferentially thereof; the switching member comprising a metal strip disposed inside the casing and a forked element presenting a digitally movable head outside 110

- the casing and having arms extending through the slot and the strip, the arms having a width corresponding to that of the slot so as to guide the switching member,
- 5 the strip having portions engaging the bore of the casing and another portion extending inwardly of the casing and adapted to contact with the holder when the switching member is in one position.
- 10 5. In a lighting device, a lamp bulb, a metallic casing housing the base portion thereof and connected to one terminal of a circuit; a metallic lamp-bulb holder comprising a substantially U-shaped member having 30
- 15 its bight rigidly secured to the casing and having each shank provided at its free end with a laterally extending arm, the said arms being concaved toward each other and gripping the base of the lamp bulb between 35
- 20 them; means insulating the lamp-bulb holder from the casing; a contact member insulated from the said holder and casing and connected to the other terminal of the circuit; and a metal switching member movably 40
- 25 mounted on the casing, the holder having 45
- one shank provided with an additional arm disposed so as to be engaged by the switching member when the latter is in one position.
6. In a lighting device, a lamp bulb, a metallic bulb holder, a metallic casing having a tubular portion housing the holder, and a resilient metallic switching element mounted upon and guided by the said casing portion for slidable movement circumferentially thereof and having one end portion adapted in one position to contact with the holder, the switching element being disposed within the bore of the said casing portion and having a general curvature of greater radius than the said bore; and means connecting the switching element to the said casing portion and drawing the said element against the said casing portion to flex the said element to a reduced radius, thereby causing friction for preventing accidental movement of the said element.

Signed at Chicago, Illinois, July 13th, 1925.

JAMES J. GOUGH.
